UNITED STATES PATENT OFFICE.

JAMES S. CLAY, OF INDIANAPOLIS, INDIANA, ASSIGNOR TO CALDWELL & DRAKE IRON WORKS, OF COLUMBUS, INDIANA, A CORPORATION OF INDIANA.

POST-RETAINING MEMBER.

Application filed December 19, 1921. Serial No. 523,441.

To all whom it may concern:

Be it known that I, JAMES S. CLAY, a citizen of the United States, residing at Indianapolis, in the county of Marion and 5 State of Indiana, have invented certain new and useful Improvements in Post-Retaining Members, of which the following is a specification.

This invention relates to post retaining members and is designed primarily for use in connection with that class of post constructions shown in my co-pending application, Serial No. 506,183, filed October 7, 1921. The prime feature of the present invention is to provide means for retaining the post in substantially upright position should the post be delivered a blow sufficient to break it loose from its anchoring means thereby preventing the breakage of the 10 globe or other parts connected with the post, and also eliminating any possibility of the post striking a pavement with sufficient force to break the same, and also prevent the post striking pedestrians.

25 A further feature of the invention is the provision of anchoring means in the base block for supporting the retaining member, such supporting means being so constructed that the retaining member may be readily 20 entered therein.

Other objects and advantages will be hereinafter more fully set forth and pointed out in the accompanying specification.

In the accompanying drawings,

35 The figure represents a lamp post and parts of its anchoring base, parts of the post being shown in section, and the retaining member positioned therein.

Referring to the drawing, 1 indicates the 40 post which is preferably hollow and formed of metal, the base of the post being anchored to a supporting block 2 by means of clips 3 and bolts 4, the head ends of the bolts being anchored in the block and extended through the clips so as to bind the 45 clips on the rib 5 at the bottom of the post.

The clips 3 are of such fragile nature that a blow delivered to the post will snap the clips in two and thereby protect the post 50 against breakage from the blow delivered, but under ordinary circumstances the post, when released from its anchoring means would fall over and not only break the globe, but under extreme circumstances

might break the post or strike and injure 55 pedestrians. To obviate these objectionable features, a retaining member 6 is extended part way through the post and the lower end thereof is entered in a socket 7 embedded in the block 2, the retaining member having a 60 more or less loose fit in the socket. The retaining member 6 may be formed of a section of pipe or may be solid, as may be desired, and extends upwardly into the post a sufficient distance to prevent the post falling over when broken loose from its base, and in the event an unusually hard blow is delivered, the member will bend rather than 65 break, consequently preventing the post from striking the ground or pavement, as 70 would occur in the absence of the retaining member.

In applying the post and retaining member to use, the retaining member is placed 75 within the post and the post then set in an upright position over the block and the clips applied to use to hold the post in upright position, this being accomplished by providing an opening 8 in the base portion of 80 the post. After the post has been properly anchored the lower end of the retaining member is brought into registration with the socket 7 and then lowered into the socket, thus completing the erection of the post. After this operation is completed the cover 85 plate 9 is fastened over the opening 8, thus completely enclosing the anchoring parts and the retaining member. By providing the socket in the supporting block for the post and entering the retaining member 90 therein, after the post is placed in position, the necessity of lifting the post over the top of the retaining member is obviated and rendering it comparatively an easy matter 95 to set up the post.

Having thus fully described my said invention, what I claim as new and desire to secure by Letters Patent, is:

1. The combination with a hollow post and means for anchoring the same in an 100 upright position, of a retaining member within said post, means for supporting the retaining member said retaining member holding said post in substantially upright position only upon fracture of said anchoring means for the post, substantially as set forth.

2. The combination with a hollow post, a

supporting block, and means for anchoring the post to said block, of a retaining member extending into said post, and a socket embedded in the supporting block for anchoring the lower end of the retaining member.

In witness whereof, I have hereunto set

my hand and seal at Indianapolis, Indiana, this 10th day of December, A. D. nineteen hundred and twenty-one.

JAMES S. CLAY. [L.S.]

Witnesses:

CAREY S. FRYE,
M. L. SHULER.
